UNITED STATES PATENT OFFICE

ADRIAN O. DALLER, OF MOUNT VERNON, NEW YORK, ASSIGNOR, BY DIRECT AND MESNE ASSIGNMENTS, TO DALLER CARTON CO. INC., A CORPORATION OF NEW YORK

CARTON

Application filed July 1, 1927. Serial No. 202,773.

This invention relates to a box which is both structurally and functionally improved.

It is an object of the invention to provide a box of this character which will furnish a permanent seal as well as a temporary closure, the former serving after the packing of the box to maintain the contents thereof intact until purchased by the user, and the latter being employed by the purchaser until the 10 contents of the receptacle become exhausted.

A further object of the invention is that of furnishing a box preferably of the "end-fill" type which may be readily shipped and stored to occupy a minimum of space prior 15 to its filling, and which subsequently to the latter operation will provide a relatively strong receptacle capable of withstanding rough usage of an ordinary character.

A still further object is that of furnishing 20 a box which may be readily blanked out and in which the blank may have certain of its parts joined immediately subsequently to its production without the resulting article occupying more than a minimum amount of 25 space, and in which, at the time of filling, the remaining box parts to be joined may be secured to each other with facility and economy.

Other objects of the invention will in part 30 be obvious and will in part appear herein-after.

The invention accordingly comprises an article of manufacture possessing the features, properties and the relation of elements 35 which will be exemplified in the article hereinafter described and the scope of the application of which will be indicated in the claims.

For a fuller understanding of the nature 40 and objects of the invention reference should be had to the following detailed description taken in connection with the accompanying drawing, in which:

Figure 1 is a plan view of one form of 45 blank to provide a box embodying the construction of the present invention;

Fig. 2 shows a collapsed box having cer- 50 tain of its parts joined; and

Fig. 3 is a perspective view showing the 55 completed box.

With primary reference to Fig. 1, the numeral 5 indicates the base of the blank provided with end sections 6 of a length equal to the height of the box to be formed and from the edges of which sections tabs 7 extend. Arranged one to each side of the base-portion 5 and forming a part of the blank are side walls 8 and 9, respectively, from the end edges of which flaps 10 extend. Beyond the side edge of the section 8 a cover-section 11 is provided having its outer side edge terminating in a flap 12. Beyond the side edge of the section 9 a further cover section 13 is furnished.

These several sections, flaps, tabs, etc., are 65 defined by score-lines 14, or any other suitable expedient may be resorted to so that these portions may readily be bent to extend at angles to each other, and at this time it will be observed that a preferably relatively 70 heavy score-line 15 is provided between sections 9 and 13 and which may be additional to the score-line furnished for bending. Consequently, a user may sever entirely the section 9 from the section 13 by any proper instrument.

In the embodiment of the invention shown the section 13 is illustrated as of substantially the same size as the cover section 11. If desired, the width of the overlying section 13 80 may be obviously reduced so that it forms only a narrow sealing flap joined to the wall 9 by a heavily scored or perforated line. In some cases the heavily scored or perforated 85 line, shown in the drawings as at 15, may be impressed on the section 9 in close proximity to its outer edge, leaving between the edge and the score-line a narrow sealing portion. The tucking flap 12 is, under such circumstances, long enough to extend well below the 90 score-line when the box is assembled.

It is obvious that a box blank of this order may be readily and cheaply produced, and, as stated above, this box is of that type which is particularly useful when packed by an "end fill". In order to expedite the subsequent complete assemblage of the box embracing the attachment of its several parts one to the other, it is desired that certain 95 of the sections thereto be partially joined 100

prior to shipment and at the time of manufacture of the blank. To this end, as has been shown particularly in Fig. 2, the cover-section 11 is folded inwardly to overlie the side-wall-section 8, and the side-wall-section 9 is folded inwardly to overlie the base 5, the cover-section 13 overlying and being conveniently secured to the upper face of the cover-section 11 in any suitable manner, as, for example, by glue. Thus, an article is produced (as shown in Fig. 2) which, as will be appreciated, will occupy a minimum amount of space and which will lie flat without injury to its parts.

When the box is ready to be completely set up, it will be obvious that by proper pressure the article, as in Fig. 2, may have its parts brought to a position at which its side walls extend parallel to each other and at right angles to the tops and bottoms, the ends of the box remaining open. At this time, or subsequently to the closing of one end of the box, it is filled by introducing through the opposite end thereof, in package form or otherwise, the article or articles with which it is to be filled.

Each end of the box is closed preferably as follows: The flaps 10 are bent to extend inwardly toward each other and at right angles to the side walls to which they are attached. The end-sections 6 may then have their inner faces coated with glue, as has been indicated at 16, and the upper faces of the tabs 7 likewise may present glued areas 17; it being obvious that, if the glue is applied at the time the box is manufactured and allowed to dry, at this time it will be necessary only to moisten the proper areas of the parts referred to. Thereupon, the end-sections 6 are folded upwardly so that the glued inner faces thereof engage the outer faces of the outermost flaps 10; it being understood that the flaps 7 are bent to extend inwardly at right angles to the end-sections 6 to bear against the inner face of the top section 11. The outer edges of the flaps 10 preferably are cut at a slight angle so that ample clearance will be provided between these upper edges and the inner face of the top section to permit of the introduction of the flaps, which latter preferably are tapered to facilitate such introduction. The filled box now may be shipped, and it will be obvious that if any attempt is made to tamper with the contents, this will be readily apparent to the purchaser. The latter, upon desiring access to the interior of the box, simply will cut along the score-line 15 and swing the cover upwardly, this action resulting in a breaking of the glue connection between the flaps 7 and the inner face of the cover 11. Thus the permanent seal is broken, but the cover 11, carrying with it the cover or top 13, may be swung to close and open the receptacle until such time as the latter is discarded, the initial opening result-

ing in the breaking of the connection which exists between the inner face of the cover 11 and the outer faces of the flaps 7.

Thus, among others, the objects of this invention have been accomplished, and since certain changes may be made in the above article, and different embodiments of the invention could be made, without departing from the scope thereof, it is intended that all matter contained in the above description or shown in the accompanying drawing shall be interpreted as illustrative and not in a limiting sense.

It is to be understood that the invention described and claimed herein is not to be limited by the terminology employed or the relative dimensions of the portions in the device shown in the drawing. Those parts referred to as covers may be sides, ends or bottoms and the box or carton may be taller than it is broad, etc.

Within the scope of the invention it is intended that one section or wall which may in whole or in part lie against another section or wall may be provided with a weakened or perforated line, whereby a sealed container may be unsealed by breaking along the weakened line, and wherein a portion of one of the sections which lie against each other may become available as a tucking flap for use during the period of temporary closure of the box.

It is also to be understood that the following claims are intended to cover all of the generic and specific features of the invention herein described and all statements of the scope of the invention which as a matter of language might be said to fall therebetween.

Having described my invention, what I claim as new and desire to secure by Letters Patent is:

1. A box, including, in combination, a base, side and end-wall sections extending upwardly therefrom, a cover section extending from the upper edge of one of the side wall sections, a second cover section overlying the first-named cover section and being secured thereto, said box being provided with a heavy score-line between said last-named cover section and the side wall to which it is connected, and flaps secured one to each of the upper edges of the end sections of said box and to the outer edge of the first-named cover section, the flaps of the end sections being secured to the inner face of said cover section.

2. A box, including, in combination, a base, side and end-wall section extending upwardly therefrom, a cover section extending from the upper edge of one of the side wall sections toward the top of the other side wall section and having a downwardly extending flap disposed inwardly of and paralleling said last-mentioned side wall section, a second cover section overlying the first-men-

- tioned cover section and being secured thereto, said second cover section being provided with a score-line adjacent its connection with said last-mentioned side wall section whereby said second cover section may be readily detached from said last-mentioned side wall section.
3. A box, including, in combination, a base, side and end-wall sections extending upwardly therefrom, a cover section extending from the upper edge of one of the side wall sections toward the top of the other side wall section and having a downwardly extending flap disposed inwardly of and paralleling said last-mentioned side wall section, said end-wall sections each having a flap adapted to be secured to said cover section, a second cover section overlying the first-mentioned cover section and being secured thereto, said second cover section being provided with a score-line adjacent its connection with said last-mentioned side wall section whereby said second cover section may be readily detached from said last-mentioned side wall section.
4. A box, including, in combination, a base, side and end-wall sections extending upwardly therefrom, a cover section extending from the upper edge of one of the side wall sections toward the top of the other side wall section and having a downwardly extending flap disposed inwardly of and paralleling said last-mentioned side wall section, said end-wall sections each having a flap adapted to be secured to said cover section, a second cover section overlying the first-mentioned cover section and being secured thereto, said second cover section being provided with a score-line adjacent its connection with said last-mentioned side wall section whereby said second cover section may be readily detached from said last-mentioned side wall section, certain of said side wall sections having a flap at one end thereof adapted to be folded inside of said end-wall sections when in upright position.
5. A box, including, in combination, a base, side and end-wall sections extending upwardly therefrom, a cover section extending from the upper edge of one of the side wall sections toward the top of the other side wall section and having a downwardly extending flap disposed inwardly of and paralleling said last-mentioned side wall section, a second cover section overlying the first-mentioned cover section and being secured thereto, said second cover section being provided with a score-line adjacent but slightly removed from its connection with said last-mentioned side wall section whereby said second cover section may be readily detached from said last-mentioned side wall section.
6. A carton comprising a bottom, a front wall, having a flap on its top edge, a rear wall, a cover associated with said rear wall and having a tuck on its front edge, said tuck being disposed on the inner side of the front wall, and the flap of said front wall being secured to the exterior of said cover when the latter is in covering position to form a seal for said carton, and means providing a weakened line at the juncture of the front wall and front wall flap for severing said flap from the front wall to unseal the carton whereby said cover tuck is adapted for reclosing the carton after said front wall flap is severed.
7. A carton comprising a bottom, a front wall having a flap on its top edge, a rear wall, a cover on the top edge of the rear wall, said cover having a tuck on its front edge, said tuck being unsecuredly disposed flat against the inner side of the front wall, and the flap of the front wall being secured to the marginal front portion of the exterior of said cover when the cover is in covering position for forming a seal for the carton at the top edge of the front wall, and means associated with said front wall and disposed at the juncture of the front wall and front wall flap for severing said flap from said front wall to unseal the carton, said cover tuck being adapted for reclosing said carton after said front wall flap is severed.
8. A carton formed from a blank which provides top, bottom, end and side walls, one of said walls having an extension to overlie a proximate wall, a portion of said extension being secured to said proximate wall, a score-line adjacent said portion, and a potential tucking flap associated with said un-scored wall releasable upon the perforation of said score-line for effecting temporary closure of said carton.
9. A carton having top, bottom, side and end walls, one of said walls comprising overlying sections of said carton, a score-line in one of said overlying sections, a portion of said sections being intersecured and adapted upon the perforation of said score-line to remain intersecured and a part of that section having no score-line being adapted to form a tucking flap.
10. In a box, the combination comprising side walls, a cover extending from the upper edge of one of said walls toward the top of another of said walls and having a downwardly-extending flap paralleling said last-mentioned wall, and a second cover extending from the upper edge of said last-mentioned wall and provided with a score-line adjacent its connection with said wall whereby said second cover may be readily detached from said last-mentioned side wall, said covers being superimposed.
11. In a box, the combination comprising side walls, a cover extending from one of said walls and having a flap, and a second cover extending from a second of said walls and provided with a line of weakness adjacent its connection with said wall whereby

said second cover may be readily detached from said last-mentioned wall, said covers being superimposed.

12. In a box, the combination comprising
5 side walls, a cover attached to one portion of
said box, a flap extending from said cover,
and a second cover attached to another portion
of said box and provided with a score-
line adjacent its connection with said last-
10 mentioned portion, whereby said second
cover may be readily detached from said last-
mentioned portion, said covers being super-
imposed.

13. A carton having top, bottom, side and
15 end walls, one of said walls comprising over-
lying sections of said carton, a score-line in
one of said overlying sections, a portion of
said sections being intersecured and adapted
20 upon the perforation of said score-line to re-
main intersecured and a part of that section
having no score-line being adapted to form a
tucking flap, said section and tucking flap
providing a hinged closure for said carton.

25 In testimony whereof I affix my signature.

ADRIAN O. DALLER.
